UNITED STATES PATENT OFFICE.

OTTO M. GILBERTSON, OF LA CROSSE, WISCONSIN.

MACHINE FOR CUTTING AND FEEDING SANITARY PAPER COVERINGS FOR CLOSET-SEATS.

1,081,904.

Specification of Letters Patent. Patented Dec. 16, 1913.

Application filed February 18, 1913. Serial No. 748,225.

To all whom it may concern:

Be it known that I, OTTO M. GILBERTSON, a citizen of the United States, residing at La Crosse, in the county of La Crosse and State of Wisconsin, have invented certain new and useful Improvements in Machines for Cutting and Feeding Sanitary Paper Coverings for Closet-Seats; and I do declare the following to be a full, clear, and exact description of the invention, such as will enable others skilled in the art to which it appertains to make and use the same.

This invention relates to improvements in means for cutting and feeding sanitary paper coverings for closet seats.

One object of the invention is to provide a machine of this character adapted to be applied to a closet seat for cutting paper coverings therefor and for feeding said coverings onto the seats in position for use.

Another object is to provide an improved construction or covering or closure adapted to be brought into and out of engagement with the seat by the machine.

With these and other objects in view, the invention consists of certain novel features of construction, and the combination and arrangement of parts as will be more fully described and claimed.

In the accompanying drawings, Figure 1 is a front elevation of a closet bowl and seat showing my invention applied thereto; Fig. 2 is a side view of one side thereof; Fig. 3 is a rear view of the machine; Fig. 4 is a vertical cross section thereof taken on the line 4-4 of Fig. 1 showing the closure for the seat and bowl in an open or inoperative position and one of the sanitary paper seat coverings in position on the seat; Fig. 5 is a horizontal sectional view taken on the line 5-5 of Fig. 4; Fig. 6 is a similar view showing the closure of the seat and bowl in an operative position; Fig. 7 is a detail perspective view of the movable member of the paper cutting die of the machine; Fig. 8 is an inverted perspective view of one of the cutting blades of the movable member of the die shown in Fig. 7; Fig. 9 is a detail perspective view of the knives for severing the paper after the coverings have been

formed therefrom and fed to an operative position over or in engagement with the seat; Fig. 10 is a detail perspective view of one of the blades of the stationary member of the paper cutting die; Fig. 11 is a similar view of one of the paper coverings formed by the machine.

In the embodiment of the invention I provide a main supporting frame which may be of any suitable shape and which is adapted to be secured to the rear portion of the seat 2 of the closet bowl in any suitable manner. In the present instance the frame is shown as comprising vertical side bars 1 which are connected at their lower ends by a lower crossbar 3 and at a suitable distance above the cross bar 3 are connected by an upper cross bar 4. The side bars are extended upwardly for a suitable distance above the cross bar 3 and have arranged thereon bearings to revolvably support the shaft 5 of a roll of paper from which my improved sanitary seat coverings are formed.

Secured to the side bars 1 opposite the upper cross bar 4 of the frame is a diamond-shaped die supporting frame 7 the lower end of which is also connected to the lower cross bar 3 of the frame by an integral extension 8 as shown. Secured to the front sides of the frame 7 are stationary die members or blocks 9 which are arranged to form a diamond shaped opening and to which are secured the stationary cutting blades 10 of the female die. Adapted to co-act with the stationary die member of the machine is a movable male die comprising a diamond-shaped frame 11 in which is arranged a centrally disposed cross bar 12. The bar 12 has secured thereto and projecting at right angles thereto rods 13 which slidably engage brackets 14 in the upper cross bar 4 of the frame 1 and thereby support the movable member of the die in position to be brought into operative engagement with the stationary member thereof. The movable member of the die carries a series of cutting blades 15 which are provided near their inner ends with inwardly extending right angular attaching lugs 16 which project inwardly and have

their inner ends overlapped and secured to bosses 17 on the front side of the frame 11 by pivot screws or bolts 18 as clearly shown in Fig. 7 of the drawings. The outer portions of the blades 15 are loosely secured to the adjacent portions of the frame 11 by means of bolts 19 which are arranged in notches or recesses 20 formed in the front side of the frame 11. The inner ends of the 10 bolts 19 are loosely engaged with apertures in the inner walls of the recesses 20 and have thereon adjusting nuts 21.

Arranged on the bolts 19 are coiled springs 22 the pressure of which is exerted 15 to force the outer portions of the blades outwardly or away from the edges of the frame so that when the movable die member is brought into coaction with the stationary die member, said blades will form a positive cutting engagement with the blades of the stationary die. The engagement of the blades 15 with the stationary blades 10 of the die blocks 9 will force said yielding or spring projected blades of the movable die member 20 inwardly so that when the cuts are completed the blades 15 will have been forced into contact with the edges of the frame 11. The blades 15 are of greater width at their inner ends than at their outer ends, the cutting edges of the blades tapering from said inner ends toward the outer ends as clearly 25 shown in Figs. 7 and 8 of the drawings. By thus constructing the blades 15 it will be seen that when the movable die member is 30 brought into engagement with the stationary die member the inner ends of the blades 15 begin cutting the paper first and the paper is gradually cut toward the outer ends of the blades as the edges thereof are 35 brought into coaction with the outer portions of the stationary die blades, the blades 40 thus having a shearing action when cutting the paper.

The paper from which the sanitary seat 45 coverings are formed is unwound from the roll 6 and drawn downwardly between the stationary and movable members of the die and is fed from the roll and the coverings formed thereon projected across the closet 50 seat by the feeding mechanism hereinafter described. The movable die member 11 is actuated to cut an opening in the paper between said die members by an operating mechanism comprising a short rack bar 23 55 secured at one end to the cross bar 12 of the frame 11 and which has a sliding engagement with the upper edge of the upper cross bar 4 of the main frame of the machine as shown. Revolubly mounted in suitable 60 bearing brackets on the bar 4 of the main frame is a rock shaft 24 having fixed on its inner end a pinion 25 which has an operative engagement with the rack bar 23 whereby when the shaft 24 is rocked in one direction

or the other the rack bar 23 and the movable 65 member of the die will be projected and retracted into and out of engagement with the stationary die member thereby cutting the portion of the paper between said die members. The blades 15 of the movable die 70 member do not come together at their lower ends, so that the cut made in the paper by the blades of the movable and stationary die members is not completed at the lower portion, or in other words the portion of the 75 paper cut out by the blades is not entirely severed from the main sheet or strip of paper so that when the portion of the sheet which forms the sanitary seat covering is projected over or into engagement with the 80 seat of the bowl, the cut out portion will hang down in the form of a tab or apron, and will cover the front edge of the hole in the seat and the front inner portion of the bowl. The rock shaft 24 is provided on its 85 outer end with a short crank arm 26 to which is connected the upper end of an operating rod or bar 27 the lower end of which is connected with the paper severing mechanism of the machine hereinafter described. 90

After the dies have been operated to cut the opening in the paper as hereinbefore described the paper is fed or drawn from the roll and the cut portion thereof projected over or into engagement with the seat of the 95 bowl by a paper feeding mechanism comprising a pair of feeding rolls 28 and 29 which are revolubly mounted in the side bars of the main frame near the lower cross bar 3 thereof. The rolls 28 and 29 are provided with a covering of rubber or other suitable material for obtaining a firm grip on the paper. The rollers 28 and 29 are provided at one end with operating gears 30 and 31 which are normally engaged for operating 100 said rollers. The gear 30 on the upper roller 28 is slidably keyed to said roller and is adapted to be shifted laterally thereon out of engagement with the gear 31 on the lower roller 29 and out of engagement with a 110 driving gear 32 fixed on a pulley shaft 33 which is revolubly mounted in the side bars of the frame above the upper roller 28 as shown. The gear 30 is shifted into and out of engagement with the gears 31 and 32 by 115 a shifting mechanism comprising a shifting bar 34 slidably mounted in a bearing bracket 35 formed on the adjacent side bar of the frame and which is provided on its inner end with a fork 36 adapted to loosely engage 120 a flanged hub 37 formed on the outer side of the gear 30. On the outer end of the bar 34 is secured a plug 38 having therein a recess 39 with which is loosely engaged a depending finger 40 formed on the lower end 125 of a gear shifting lever 41 which is fulcrumed on bearing ears 42 formed on the bracket 35 as shown. By swinging the lever

41 inwardly or outwardly the gear 30 will be shifted out of and into operative engagement with the drive gear 32 and the gear 31 on the lower feed roller whereby the movement of the drive gear 32 will be imparted to said feed rollers.

42 The pulley shaft 33 and the drive gear 32 thereon are operated by a suitable driving mechanism comprising a power transmitting shaft 43 which is revolvably mounted in suitable bearings in the side bars of the frame and has fixed thereon adjacent to one end a power transmitting gear 44 which is engaged with a pinion 45 on the adjacent end 46 of the pulley shaft 33 as shown. Also fixed on the shaft 43 is a sprocket gear 46 which is connected by a sprocket chain 47 with a sprocket gear 48 revolvably mounted on a stub shaft 49 which is adjustably secured in a slot 50 formed in the extended upper portion of the adjacent side bar of the frame 1 as shown. The upper sprocket gear 48 is provided with a crank handle 51 whereby this gear is turned for actuating the power transmitting shaft 43 the movement of which is imparted to the pulley shaft and through the latter to the feeding rollers in the manner described for turning said rollers in the proper direction.

47 The cutting mechanism for severing the paper after the same has been cut by the dies and fed across or over the seat of the bowl by the feeding rollers 28 and 29 hereinbefore described, and between which the 55 end of the paper is always engaged, comprises a lower cutting bar or blade 52 the ends of which are pivotally connected to the lower ends of short operating bars or levers 53 and 54 which are pivoted midway between their ends to the side bars of the main frame of the device. To the upper end of the bar or lever 53 is pivotally connected an upper knife or cutting blade 55 while to the upper end of the lever 54 is pivotally connected an upper knife or cutting blade 56. The lower or cutting edges of the knives or blades 55 and 56 are formed on an angle or inclined upwardly from their outer toward their inner ends as shown. To the 60 lower corner of the pivoted end of the blade or knife 56 is connected one end of a blade or knife operating rod 58 the opposite end of which is pivotally connected to the shank 59 of a blade operating handle 60 which is formed on and projects upwardly at an angle from the outer edge of the lever 53 and from a point midway between the ends of said lever as clearly shown in Fig. 9 of the drawings. The rod 58 is offset or bent 65 downwardly at its end and the offset inner end thereof is slidably engaged with a stud 61 on the lower outer corner of the upper blade or knife 55 as shown. By thus constructing and arranging the upper and lower blades of the cutting mechanism and 65 providing the operating shaft as herein shown and described it will be seen that when the handle 60 is pressed downwardly the lever 53 will be rocked and through the lower cutting bar or blade 52 will rock the 70 lever 54 on the opposite side of the frame and will raise said bar or blade 52. Simultaneously with the operation of the blade 52 the rod 58 will be actuated by the handle 60 and will swing the upper cutting blades or 75 knives 55 and 56 downwardly into operative engagement with the upwardly moving lower cutting bar or blade 52 thereby severing the end of the strip of paper which has been cut by the dies to form the seat covering and has been projected forwardly over the seat by the feeding rollers 28 and 29 hereinbefore described. The operating rod or bar 27 which is connected at its upper end to the crank arm 26 on the rock shaft 24 has its lower end connected to the upper end of the knife operating lever or bar 53 as shown at 62 so that when the knives or cutting blades of the paper severing mechanism are actuated the rock shaft 24 will 80 be simultaneously operated to project the movable member of the paper cutting die into engagement with the stationary member thereof for cutting the opening in the portion of the paper which is now between 85 the die members as hereinbefore described thus forming the next seat covering.

48 In connection with my improved sanitary paper coverings and the means for cutting and projecting the same into position over 100 the seat I also provide an especially designed cover for the seat when the latter is not in use. My improved seat cover is in the form of an apron 63 which is secured at its outer end to and is adapted to be wound on and off a supporting roller 64 which is mounted in suitable brackets 65 secured to the front edge of the closet seat as shown. The apron 63 which forms the cover of the seat may be constructed of leather, cloth or other 105 suitable flexible material which may be readily wound on and off the roller. The outer end of the apron 63 has secured there-to a binding strip 66 formed of metal or other suitable material. The apron 63 is 110 drawn back and forth across the seat, to cover and uncover the same, by endless operating cords 67 which are engaged with the ends of the roller 64 at the forward end 115 of the seat and at the rear end of the seat 120 are operatively engaged with pulleys 68 fixed on the pulley shaft 33 hereinbefore referred to and which is revolvably mounted in the side bars of the main frame of the device. As hereinbefore described the 125 pulley shaft 33 has fixed on its outer end a pinion 45 which is operatively engaged with a gear 44 on the power transmitting shaft

43 which is driven by the sprocket chain 47 and sprocket gears which have also been previously described in connection with the operating mechanism for paper feeding 5 rollers 28 and 29. The apron operating cords 67 before engaging the pulleys 68 have one stretch thereof engaged with guide pulleys 69 and the other stretch engaged with guide pulleys 70 which are arranged on the 10 base of the main supporting frame and which hold and guide the cords so that the latter will be properly engaged with and operated by the pulleys 68 for drawing the apron over the seat when the latter is not in use and which will operate the roller to draw the apron forwardly from the seat and wind the same on the roller 64. In this 15 operation the apron is drawn from the seat and wound up on the roller simultaneously with the projection of the sanitary paper seat covering by the feeding rollers 28 and 29, it will be understood however that when the apron is drawn back over the seat that, it is first necessary to shift the gear 30 of 20 the upper paper projecting roller out of engagement with the gear 32 on the pulley shaft 33 so that the paper feeding mechanism will be thrown out of operation, while the apron is being drawn across or over the 25 seat. The binding strip 66 on the outer end of the apron 63 is suitably connected with one of the stretches of the operating cord 67 so that when the cords are operated in the manner described the apron will be 30 drawn back and forth across the seat.

In practice the device will be provided with suitable casings or coverings for enclosing the operating gears and other parts of the device, said coverings being omitted 40 from the drawings to enable the parts to be more clearly illustrated.

From the foregoing description taken in connection with the accompanying drawings, the construction and operation of the 45 invention will be readily understood without requiring a more extended explanation.

Various changes in the form, proportion and the minor details of construction may be resorted to without departing from the 50 principle or sacrificing any of the advantages of the invention as claimed.

Having thus described my invention, what I claim is:

1. A paper cutter comprising a fixed die 55 having a stationary blade; and a movable die including a frame, a blade pivoted at one end to said frame in position to pass across the edge of the stationary blade, and yielding means for pressing its other end 60 away from its frame on a line substantially at right angles to the direction of movement of said frame.

2. A paper cutter comprising a fixed die having a stationary blade; combined with

a movable die comprising a frame moving 65 toward and from the fixed die, a blade pivoted at one end to said frame in position to pass the edge of said stationary blade, guides on the frame for permitting a lateral movement of the other end of said blade, and a 70 spring pressing this end of such blade normally away from the frame, for the purpose set forth.

3. A paper cutter comprising a fixed die having a stationary blade; combined with 75 a movable die comprising a frame moving toward and from the fixed die, a blade pivoted at one end to said frame in position to pass the edge of said stationary blade, the remote end of the frame having a recess 80 with an apertured inner wall, a bolt secured to this end of the movable blade and lying in said recess with its body passing through the aperture, a nut on the inner end of said bolt, and an expansive spring coiled 85 on the bolt between said wall and the blade, for the purpose set forth.

4. In a paper cutting machine, the combination with a fixed die having a stationary blade; of a movable die comprising a frame, 90 means for moving it toward and from the fixed die, a pivot screw upstanding from one end of the frame and an apertured lug upstanding from the other, a blade having an apertured lug at one end mounted on said 95 pivot screw with its body standing alongside said frame and adapted to pass the edge of the stationary blade when the frame is moved, a bolt projecting from the other end of said blade through the apertured lug 100 on the frame, and an expansive spring coiled on this bolt between said lug and this end of the blade, for the purpose set forth.

5. In a paper cutter of the class described, the combination with a female die of substantially diamond shape having stationary cutting blades; of a male die adapted to 105 coact therewith and comprising a frame with means for moving it toward and from the female die, blades pivotally mounted at 110 their inner ends on said frame and having their bodies growing narrower from their pivoted to their outer ends and standing alongside said frame, and yielding means for pressing said bodies normally away from 115 the outer ends of the frame and into shearing action with the edge of said stationary blade, as described.

6. In a machine for cutting sanitary paper coverings for closet seats, a main supporting 120 frame adapted to be secured to the closet seat, a cutter comprising a stationary member and a movable member; combined with means to slidably support said movable die member, a die operating mechanism comprising a suitably mounted rock shaft having on one end a crank arm, a pinion fixed 125 on said shaft, a rack bar secured to the

movable die member and adapted to be engaged by said pinion whereby when the shaft is rocked in one direction or the other the movable die member will be projected 5 and retracted into and out of engagement with the stationary die member.

In testimony whereof I have hereunto set

my hand in presence of two subscribing witnesses.

OTTO M. GILBERTSON.
